UNITED STATES PATENT OFFICE.

FREDERICK G. DEARWESTER, OF CINCINNATI, OHIO, ASSIGNOR OF ONE-FOURTH TO
ALLEN & ALLEN, A FIRM COMPOSED OF ALFRED M. ALLEN AND MARSTON ALLEN,
OF CINCINNATI, OHIO.

DECORATIVE MOLDING.

Application filed March 20, 1925. Serial No. 17,073.

My invention relates to the general art of decorative molding and particularly to adjustable decorative molding made of overlapping pieces which may be mounted on frame pieces of varying length. Specifically my invention relates to adjustable molding strips which may be inserted on window frames, door frames, picture frames and the like where the lengths and widths of such frames are different.

It is the object of my invention to make from embossed paper or the like, strips of molding, embossed with designs, and to have central pieces and end pieces with conforming designs adapted to overlap the central pieces so that definite sizes may be made which may be adjustably mounted on frames of different lengths and widths.

In the art it is, of course, old to apply decorative strips of molding to window frames, picture frames and the like. It has been customary to consider decorative molding as a permanent fixture which is expensive to install and which requires the labor of an expert. With decorative strips of such inexpensive material it is my object to develop a new art which will enable house owners to consider the molding attached to window frames, and picture frames much as they consider curtains and draperies so that colors and designs of molding strips may be inexpensively changed in accordance with the change in other household furnishings. The adjustment and insertion of molding strips made in accordance with my invention will be simple as certain ranges of varying sizes may be applied to a variety of widths and lengths as will be hereinafter explained and claimed.

As a marketing proposition it will be very practical as storekeepers will only need to carry in stock a few different sizes and patterns and the purchaser will be able to produce a variety of effects on frames of varying dimensions. The use of the molding strips will also present a simple and inexpensive method of changing the molding of frames that are used for different advertising posters so that suitable molding may be provided which will harmonize with posters of different colors and designs.

Referring to the drawing in which I have illustrated molding strips made in accordance with my invention, Figure 1 is a view

of a middle piece with adjustable end pieces 55 which may be overlapped over the central piece to produce any desired effect such as in the position shown over a frame in Figure 2, or overlapping still further as shown over a frame of less length as in Figure 3. The 60 central piece is, of course, not a necessary part of the molding as it may be omitted entirely and the two overlapped end pieces secured over a frame of still less length than the frame shown in Figure 3, as illustrated 65 in Figure 4.

Generally indicated at 1 is a molding strip in which the embossed central design 2 is balanced at the middle of the piece with a central design member 3. The corner pieces 4 may be provided with designs which have balancing embossed parts 5 in harmony with the central design member 3 as shown and it is further advisable to have gently sloping end parts 6 on the corner 70 pieces which will conform with the plane of the central member.

For securing the molding pieces in position on a frame nails or tacks may be used to fasten the pieces to the frame. These 75 may be inserted in holes 7 in the molding strips located in inconspicuous positions with relation to the designs. An optional method would be to secure the strips to the frame pieces with glue or the like. It is further 80 desirable for some uses to have the strips of molding formed with bent over top parts as shown at 8 and the corner pieces may be extended to conform to the shape of the 85 corners as shown at 9.

It is not my object in this application to apply for a design patent on the illustration shown nor do I wish to limit myself to the particular design shown. It is, of course, immaterial what designs are embossed on the molding strips as long as they are such as will conform to overlapping adjustment 90 on a frame.

In order to provide inexpensive molding strips as hereinbefore noted I find that it 100 is preferable to make the strips from paper and to then have them embossed and colored but inasmuch as the art of this teaching is new it is not my desire to limit myself to the use of paper. Other compositions of 105 matter and thin strips of wood may be used with equal success.

Having thus described my invention, what

I claim as new and desire to secure by Letters Patent, is:

A plurality of embossed paper molding strips, corner strips among said strips, said corner strips with articulated extended sides adapted to conform to the shape of a frame, pieces for use between the corner pieces, said pieces with extended sides adapted to con-

form to the shape of a frame between the corners, designs on said strips of molding, said designs adapted to harmonize in a plurality of longitudinal overlapping positions of the molding strips and means for securing said strips in overlapped position. 10

FREDERICK G. DEARWESTER.
